HERMAN NEAHOUS, OF SHARPSBURG, PENNSYLVANIA.

APPARATUS FOR TREATING PARAFFINE-OIL.

SPECIFICATION forming part of Letters Patent No. 231,840, dated August 31, 1886.

Application filed July 16, 1886. (No model.)

To all whom it may concern:

Be it known that I, HERMAN NEAHOUS, of Sharpsburg, in the county of Allegheny and State of Pennsylvania, have invented a new and Improved Apparatus for Treating Paraffine-Oils, of which the following is a specification.

In the ordinary method of treating frozen paraffine-oil for the separation of the oil from the wax the frozen paraffine is inclosed in small cloths and folded and laid on plates in tiers of from twenty to twenty-five packages, and by the time the press is filled the frozen oil becomes warm, and consequently the crystallized wax melts and runs out as a liquid with the oil, and when the press is run down the wax in the cloths still contain oils, which renders it necessary for the wax itself to be again folded in cloths and again submitted to the action of the press, which process involves considerable labor, time, and waste of wax; and the wax is by this process rarely completely freed from the oil, while the oil always contains some wax, which latter injures the lubricating qualities of the oil.

The object of this invention is to provide a process and apparatus that are free from the imperfections of the old method, and will make a thorough separation of the wax and oil in a most economical manner.

The invention consists of a cylindrical press provided with proper outlets, and having a filtering piston or plunger and a filtering cap or cover; and the process consists, essentially, in introducing the frozen paraffine in bulk, without wrappings, between the top of the plunger and the cap or cover.

Figure 1 represents a vertical sectional elevation of the press on line $x-x$, Fig. 2. Fig. 2 represents a vertical sectional elevation on line $y-y$, Fig. 1. Fig. 3 is a plan of the reverse of the cap or cover of the press with a portion broken away to exhibit other parts. Fig. 4 is a plan of the top of the piston. Fig. 5 is a cross-section on line $z-z$, Fig. 1.

Similar letters of reference indicate corresponding parts.

In the drawings, A represents the press-cylinder, provided with an enlarged (preferably

rectangular) top, A', on which is hinged the cap or cover D, as shown at a . At a little below its center the said cylinder A is provided with three discharge-tubes, $b b' b''$, arranged one above another, and with a pipe, c , near its bottom for the admission of the air or liquid that serves, under pressure, to force the piston or plunger B upward. This piston B is hollow and cylindrical, and a post, d , rises centrally from its bottom to support the filtering-top B' of said piston B. This piston-top B' is a circular cap, f , having perforations g made through its top for the passage of the oil, and having fastened on its top a series of raised ribs, h , that are designed to hold up the filtering-cloth k , that is stretched over them, so as to prevent said cloth k from closing the perforations g .

B'' is the flanged metallic packing-ring that fits over the top B', and is held in place by the screws $l l$, that pass down through it and into the lugs m , that project inward from the inner face of the piston B. C is a valve-ring set about the center of said piston B, and having in it an orifice, n , corresponding with an orifice, o , in the piston B, so that when in operating the device the two orifices $n o$ are brought opposite each other, and opposite one of the tubes $b b' b''$, oil will escape from the said piston B. Above and below this ring C the piston B is provided with ordinary elastic packing-rings $p p$, as shown. When no discharge from the piston B is desired during the operation the ring C may be turned so as to close the piston-orifice o .

The rectangular cover D has a grating, D', fitted in its top, and over the lower face of this grating D' a filtering-cloth, q , is stretched and held in place by strips r , of wood or other material, that are forced between the sides of the grating D' and the cover D, and said cover D is provided with a lateral discharge-pipe, D'', for the escape of oil that is forced upward by the piston B through the filtering-cloth q . Below this filtering-cloth q , and in contact with the face thereof, a scraper, E, extends across the cover D, and is held in place and moved across the face of the cloth q by the two screws E' , that pass through stuffing-boxes s .

on the front of the cover D and through said scraper E, and are pivoted in the bosses *t* in the rear side of said cover D.

5 F F are clamps designed to hold said cover D firmly closed.

To operate this device the piston B is pushed nearly to the bottom of the press-cylinder A, which cylinder A is then filled from the top with the frozen paraffine-oil to be treated. The 10 cover D is then fastened down, and water or air is forced under pressure below the piston B through the pipe *c*, thereby causing the said piston B to rise and compress the contents of the press, so that the expressed oil will flow 15 in one direction, through the filtering-cloth *k*, into the piston B, and in the other direction through the filtering medium *q* and out through the discharge-pipe D'', and as said piston B fills and rises the ring and piston-orifices *n o* respectively come opposite the tube *b*, when the oil above said orifice *o* of the piston B is forced out through the tube *b*, and as the process continues the escape of the oil from the piston B is cut off until the said orifices *n o* 25 come opposite the tube *b'*, and again cut off by the inner face of the cylinder A until said orifices *n o* are brought opposite the tube *b''*, through which the accumulated oil is discharged. 30 The number of discharge-tubes *b* may be unlimited, and the ring C and orifices *n o* may be arranged on a higher or lower level.

During the process the contained wax is likely to crystallize and adhere to the filtering-cloth *q*, and thereby interfere with the fil- 35

tering of the oil, and in order to remove said wax the scraper E is moved across the face of said filter *q* by turning the screws E'.

At the close of the operation the cover D may be thrown back and the accumulated wax 40 removed from the cylinder A.

This device is adapted for pressing other substances than frozen paraffine-oil, and when the expressed liquid requires further filtering the cover D will be made higher or deeper, 45 so that charcoal or other filtering medium may be placed above the filtering-cloth *q*.

Having thus described my invention, what I claim as new, and desire to secure by Letters Patent, is—

50 1. A press for treating paraffine-oils, constructed substantially as herein shown and described, containing the following elements: a hollow filtering-piston and a filtering-cover, as set forth.

55 2. The combination, with the press-cylinder A, provided with suitable discharge-pipes, of the hollow piston B, having lateral orifice *o*, and provided with perforated and ribbed top B' and filtering medium *k*, substantially as 60 herein shown and described.

3. The combination, with the press-cylinder A, of the cover D, having discharge-pipe D'', and provided with grating D' and filtering-cloth *q*, substantially as herein shown and de- 65 scribed.

HERMAN NEAHOUS.
